FIG. 1 is a front perspective view of my comb;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8. is a bottom perspective view thereof.

In some implementations, the comb, as shown in FIGS. 1-8, has multiple rows of bristles of various heights. In some implementations, as shown in FIGS. 1-6 and 7, a top, central portion of the front and rear sides of the comb include a plurality of protruding elongated features. In some implementations, a cylindrical base of the comb, as shown in FIGS. 1-5 and 7, includes recessed channels to enable connection to another apparatus, such as a hair drier. The broken lines shown in the figures show features of the comb that form no part of the claimed design.
